FIG.1

FIG.3

FIG.2

FIG.4

FIG.8

FIG. 1 is a perspective view of a toboggan showing my new design;

FIG. 2 is a perspective view of a toboggan showing a second embodiment of my new design in partially folded condition, wherein the only difference resides in the omission of one of the rear sections and hinge connection;

FIG. 3 is a perspective view of a toboggan showing a third embodiment of my new design, wherein the only difference resides in the omission of both rear sections and hinge connections;

FIG. 4 is an enlarged side elevational view of the embodiment shown in FIG. 1 in folded condition;

FIG. 5 is an enlarged top plan view of the embodiment shown in FIG. 1, with the cushions removed and the rear section broken away in the center for convenience of illustration;

FIG. 6 is a side elevation view of FIG. 5;

FIG. 7 is a bottom plan view of FIG. 5; and

FIG. 8 is a sectional view to a greatly enlarged scale taken along the lines 8-8 in FIG. 6 and looking in the direction of the arrows.

I claim:

The ornamental design for a toboggan, as shown and described.
